THOMAS McCABE, OF YORKVILLE, OHIO.

PLATE-LIFTING MECHANISM FOR ROLLING-MACHINES.

1,389,521.

Specification of Letters Patent. Patented Aug. 30, 1921.

Application filed June 17, 1919. Serial No. 304,825.

To all whom it may concern:

Be it known that I, THOMAS McCABE, a citizen of the United States, residing at Yorkville, Ohio, have invented a certain new and useful Improvement in Plate-Lifting Mechanism for Rolling-Machines, of which the following is a full, clear, and exact description, such as will enable others skilled in the art to which it appertains to make and use the same.

This invention relates to sheet metal plate rolling machines of the kind in which the plates are passed numerous times through the rolls of the machine.

15 In operating sheet metal plate machines or rolling mills of the character referred to it is the universal practice to employ one operative, generally termed a "roller", who stands in front of the rolls of the machine 20 and feeds the plates rearwardly through the rolls and two operatives, generally termed "catchers", who stand at the rear of the rolls so as to receive the plates and lift them upwardly onto the top roll of the machine 25 into such a position that the roller can grasp the plates, pull them forwardly and then feed them through the rolls again.

The main object of my invention is to provide a practicable mechanism that is adapted to be used in conjunction with a sheet metal plate machine or rolling mill for receiving the plates as they are delivered from the rolls and moving the plates upwardly into such a position that they can be grasped 35 by the roller stationed at the front of the machine, thereby overcoming the necessity of employing two catchers for each machine or mill, as is now the universal practice.

To this end I have devised a mechanism 40 that comprises means arranged at the rear of the rolls of a sheet metal machine or rolling mill for raising or elevating the plates after they have been discharged from the rolls of the mill and holding the 45 plates in such a position that the operative stationed at the front of the machine can reach over the top roll of the machine, grasp the plates and then draw them forwardly over the top roll of the machine preparatory 50 to again feeding the plates rearwardly through the rolls. My invention can be used successfully for handling various kinds of objects, but it is particularly applicable either to cold mills or hot mills, namely, ma-

chines for rolling plates cold or hot. Various other means than those herein illustrated can be employed for receiving the plates as they are discharged from the rolls and lifting the plates or moving them upwardly into position to be engaged by the roller stationed in front of the mill, and therefore, I do not wish it to be understood that my invention is limited to a mechanism of the exact construction herein shown.

Figure 1 of the drawings is a front elevational view of a sheet metal plate machine or rolling mill equipped with a plate lifting mechanism constructed in accordance with my invention.

Fig. 2 is a side elevational view of said machine, showing the plate lifter carriers in their depressed position.

Fig. 3 is a top plan view of the machine.

Fig. 4 is a side elevational view, showing the plate lifter carriers in their raised position.

Fig. 5 is a vertical sectional view, taken on the line 5—5 of Fig. 3, looking in the direction indicated by the arrows.

Fig. 6 is a vertical sectional view, taken on the line 6—6 of Fig. 3, looking in the direction indicated by the arrows.

Fig. 7 is a top plan view, illustrating part of the mechanism that is employed for swinging one of the plate lifters relatively to its carrier.

Fig. 8 is a perspective view of one of the plate lifter carriers of a mechanism that is particularly designed for use with a hot mill or machine for rolling hot plates; and

Fig. 9 is a side elevational view, illustrating the way that I prefer to construct the table when the mechanism is designed for use with a hot mill.

In the machine herein illustrated, which is designed to roll cold plates, A and B designate the top and bottom rolls, respectively, of the machine, and 1 designates the main drive shaft of the machine, which is operatively connected with said rolls in such a manner that the rolls A and B will operate continuously when the drive shaft 1 is in operation. A stationary table or support C of any preferred construction is arranged at the rear of the rolls A and B so as to receive the plates as they are delivered from the rolls, and means is provided for lifting said plates or moving them upwardly from

the table C and holding the plates in such a position that they can be grasped easily by the roller or operative stationed at the front of the machine who pulls said plates forwardly and thereafter feeds them through the rolls A and B, these operations being repeated numerous times until the plates have been rolled to the proper degree.

In the form of my invention illustrated in Figs. 1 to 7, inclusive, which is designed for use with a cold roll mill, the means that is employed for lifting the plates from the table C and holding said plates in position to be grasped by the roller consists of two plate lifters D and D' arranged longitudinally of the table C at opposite sides of same and mounted on vertically movable carriers E and E', respectively, said plate lifters being covered with material d of such a character that it will not mar or scratch the finished plates. Said carriers are adapted to be moved upwardly from the position shown in Fig. 2 into the position shown in Fig. 4 and the plate lifters D and D' are mounted on said carriers in such a manner that said plate lifters can assume a vertical position at right angles to the top surface of the table C, as shown in full lines in Fig. 1, or a horizontal position parallel to the top surface of the table C, as shown in broken lines in Fig. 1. Normally the carriers E and E' stand in their elevated position shown in Fig. 4 with the plate lifters D and D' in a horizontal position. Assuming that a plate has been fed through the rolls A and B of the machine and that the operator in charge of the machine desires to pass said plate through the rolls A and B again, the operator actuates a device which causes the plate lifting mechanism to become operative. During the first step of the cycle of said mechanism the carriers E and E' move downwardly and the plate lifters D and D' on said carriers swing from a horizontal into a vertical position so that said plate lifters will not strike against the plate which is then resting on the table C. After the carriers E and E' have reached their depressed position the plate lifters swing into a horizontal position so that they will be positioned underneath the plate lying on the table C. Thereafter said carriers E and E' move upwardly into the position shown in Fig. 4 and come to rest automatically, thus holding the plate in such a position that the operative stationed at the front of the machine can grasp the front end of said plate and draw it forwardly over the top roll A of the machine preparatory to passing the plate through the rolls A and B again, the carriers E and E' remaining in their elevated position until the operative again actuates the device which renders the plate lifting mechanism operative. The

plate lifters and the plate lifter carriers that are arranged at the opposite sides of the table C are of substantially the same construction. Accordingly, wherever I refer to the parts or devices that coöperate with one plate lifter or one plate lifter carrier, it will be understood that similar parts or devices designated by corresponding reference characters are associated with the other plate lifter and plate lifter carrier. As shown in Figs. 2 and 4, the carrier E is supported at its front end by a substantially bell-crank-shaped lever 2 pivotally connected thereto and at its opposite end, or rear end, by a link 3, the lever 2 having its upper end pinned to a shaft 2^a and the link 3 having its upper end pinned to a shaft 3^a. Said lever and link each consists of a relatively wide device provided with two spaced side portions, as shown in Fig. 3, whose ends are connected together by cross pieces or hubs so as to impart sufficient rigidity and strength to said lever and link to eliminate the possibility of the carrier tilting side-wise with relation to said lever and link. The shafts 2^a and 3^a are journaled in bearings on a supporting structure F, and means is provided for turning said shafts so as to swing the lever 2 and link 3 upwardly and downwardly, and thus raise and lower the carrier E. The means herein illustrated for rocking the shafts just referred to consists of an oscillating actuating member G that is carried by the supporting structure F and which is provided at its upper end with two racks 5 and 6, as shown clearly in Figs. 2 and 4. The rack 5 meshes with a gear 5^a secured to the shaft 2^a and the rack 6 meshes with a gear 6^a secured to the shaft 3^a. Accordingly, when the actuating member G rocks forwardly or to the right, looking at Fig. 4, the shafts 2^a and 3^a will turn in a direction to move the plate lifter carrier E downwardly into the position shown in Fig. 2. When said actuating member G rocks in the opposite direction the carrier E will move upwardly back to the position shown in Fig. 4. In order to assist the actuating member G to lower and raise the carrier E, the shafts 2^a and 3^a are provided with counterweights 2^b and 3^b, respectively. The plate lifter carrier E' that is arranged at the opposite side of the table C is operated by an actuating member G' illustrated in Fig. 5, said actuating member G' being rigidly connected to the actuating member G by a cross shaft 4 that is journaled in bearings in the two supporting structures F and F' arranged at opposite sides of the table C. Rocking movement is imparted to the actuating member G and G' by means of cams 7 and 7^a on a transversely-disposed cam shaft 8 which is journaled in bearings in the supporting structures F and F'. When the cam shaft 8 starts to rotate the

cam 7 thereon bears against a roller 170 on the actuating member G and rocks said member G forwardly from the position shown in Fig. 4 into the position shown 5 in Fig. 2. Thereafter, the cam 7^a on said cam shaft bears against a roller 170^a on the actuating member G' and rocks said actuating member G' rearwardly. In view of the fact that the actuating members G 10 and G' are rigidly connected together by the cross shaft 4, it will be obvious that the forward movement that is imparted to the actuating member G by the cam 7 will be transmitted to the actuating member G' 15 and that the rearward movement which is thereafter imparted to the actuating member G' will be transmitted to the actuating member G. The cam shaft 8 is rotated intermittently by a sprocket chain 9 20 which passes around a sprocket wheel 9^a on said cam shaft and around a sprocket wheel 9^b on an intermittently operating shaft H which will be hereinafter described. When the plate lifter carriers E and E' are 25 in their depressed position they lie in a substantially horizontal plane, as shown in Fig. 2. When said carriers are in their elevated position, however, as shown in Fig. 4, the front ends of same tilt downwardly slightly 30 so as to hold the plate on the plate lifters D and D' in such a position that the operator can easily draw said plate forwardly off the plate lifters. This slight upward tilt to the rear ends of the carriers E and E' 35 is obtained by connecting the links 3 to said carriers in such a manner that the distance between the centers of the shafts 3^a and the point of connection of the links 3 with said carriers will be increased automatically, 40 thus virtually lengthening the links 3 when said carriers move upwardly. It will be obvious that this action can be obtained in various ways, but I prefer to provide each of the links 3 with an eccentric strap *x* that 45 loosely surrounds a floating eccentric *y* which is pivotally connected at *z* to the carrier with which said link co-operates, as shown in Figs. 2 and 4. Each of the plate lifters is rigidly connected to a horizontally-disposed shaft 10, shown in Fig. 1, that is journaled in bearings on the carrier for said plate lifter, and the movement of said plate lifter from a horizontal into a vertical position and then back into a horizontal 50 position is effected by rocking the shaft 10. In the form of my invention herein illustrated the means for rocking each of the shafts 10 consists of an arm 11 on said shaft whose upper end 55 is pivotally connected to a curved link 12 that is pivotally connected to a rigid arm 13 on a rock shaft 14, as shown in Fig. 1. The rock shaft 14 which is arranged at right angles to the axis of movement of the plate 60 lifter is provided with a bevel gear 15, 65 shown in Figs. 1, 2 and 7, which meshes with a bevel gear 16 secured to a short stub shaft 17 that is arranged at right angles to the shaft 14, as shown in Fig. 7, and which is journaled in bearings in the plate lifter carrier. The shaft 17 is provided with a pinion 18 that is connected by means of an idler 19 with a gear 20 secured to a loose sleeve 21 on the shaft 2^a, as shown in Fig. 3, the sleeve 21 being provided with a pinion 22 that 70 meshes with a rack 23 on the upper end of a plate lifter actuating member I shown in Figs. 2 and 4. A similar plate lifting actuating member I' is arranged at the other side of the table C for actuating the plate lifter D', and said plate lifter actuating members I and I' are rigidly connected together by a cross shaft 24 which is journaled in bearings in the supporting structures F 75 and F'. The cam shaft 8 previously referred to is provided with two cams 25 and 25^a for actuating the members I and I', the cam 25 co-operating with a roller 26 on the member I, as shown in broken lines in Fig. 2, and the cam 25^a co-operating with a roller 26^a on the member I', as shown in Fig. 6. During the first part of the cycle the cam 25 rocks the members I and I' forwardly, thereby causing the plate lifters 80 D and D' which are then in a horizontal position to swing downwardly into a vertical position, due, of course, to the movement that is imparted to the shafts 10 by means of the gears and pinions arranged between the shafts 10 and the racks 23 on the upper 85 ends of the members I and I'. After the plate lifter carriers reach their depressed position, as shown in Fig. 2, the cam 25^a on the cam shaft 8 engages the roller 26^a on the member I', and thus causes both of the 90 members I and I' to swing rearwardly back to their normal position, shown in Fig. 4, thereby moving the plate lifters D and D' 95 into a horizontal position. The supporting structures F and F' that 100 are arranged at the opposite sides of the table C are mounted on a bed plate J in such a manner that one or both of said supporting structures can be adjusted laterally with reference to the table C so as to adapt 105 the mechanism to plates of various widths. In the machine herein shown the supporting structure F' is slidably mounted on guide-ways on the bed plate J, and set screws or other suitable devices 27 are provided for 110 holding said supporting structure F in adjusted position. The cams on the cam shaft 8 are keyed to same in such a manner that they can be adjusted longitudinally of the cam shaft, and the two carriers E and E' are 115 tied together by means of a tie bar 28 that passes through bearings in said carriers and which is secured to same by set screws 29, 120 as shown in Fig. 3. The operation of the plate lifting mecha- 125 130

nism above described is governed by a clutch under control of the operator in charge of the machine. As shown in Fig. 1, a transversely-disposed shaft 30 is arranged horizontally in bearings in the frame of the machine that carries the rolls A and B, said shaft 30 being adapted to be driven from any suitable source of power. In the form of my invention herein shown a belt 31 is employed for driving said shaft 30 from the main drive shaft 1 of the machine and said shaft 30 is provided at one end with a gear 32 that meshes with a gear 33 loosely mounted on the intermittent shaft H previously referred to. A clutch member 34 is keyed to the shaft H, and a coöperating clutch member 34^a is secured to the loose gear 33, the clutch member 34 being acted upon by a spring 35 that exerts pressure on same in a direction tending to move it into engagement with the clutch member on the loose gear 33. The intermittent shaft H is provided with a gear 36, shown in Fig. 3, that meshes with a relatively large gear 25 wheel 37 to which a cam 38 is attached. This cam 38 coöperates with a roller 39 on the upper end of a lever 40 secured to a horizontally-disposed shaft 41 that is journaled in bearings on the frame of the mill, as shown in Figs. 2 and 4. The shaft 41 is provided with a second arm 42, shown in broken lines in Fig. 2, whose upper end is bifurcated and arranged in engagement with a locking plunger 43 that normally holds the clutch member 34 out of engagement with the clutch member 34^a on the loose gear 33, the clutch member 34 being provided with a cam 134, as shown in Fig. 3, with which the inner end of the locking plunger 43 coöperates. When the clutch members 34 and 34^a are in engagement with each other the shaft H will rotate with the constantly rotating shaft 30, thereby causing the clutch controlling cam 38 to revolve. At a certain point in the cycle of operation of said clutch controlling cam 38 the shaft 41 rocks rearwardly under the influence of a spring 44 connected to the arm 40 on said shaft, thereby causing the plunger 43 to be pushed rearwardly into the path of the cam 134 on the clutch member 34, said cam being so shaped that after it has been engaged by the plunger 43 it causes the clutch member 34 to be moved longitudinally of the shaft H out of engagement with the clutch member on the loose gear 33, thereby causing the shaft H to come to rest. As soon as the shaft H stops the clutch controlling cam 38 comes to rest in such a position that the locking plunger 43 will remain in its operative position in engagement with the clutch member 34. To start the plate lifting mechanism the operator pulls downwardly on the hand lever 45 that is connected to the shaft 41, or depresses a foot pedal 65 46 that is connected by means of a link 47

with the hand lever 45, thereby causing the arm 42 on the shaft 41 to retract the locking plunger 43 or move it out of engagement with the clutch member 34. As soon as said clutch member is released from the locking plunger the spring 35 moves said member into engagement with the clutch member on the loose gear 33, thereby causing the shaft H to start to rotate and to continue in operation until the clutch controlling cam 38 reaches such a position that the locking plunger 43 will move rearwardly and disengage the two coöperating clutch members 34 and 34^a. 70 75

A plate lifting mechanism of the construction above described, when used in conjunction with a rolling mill or sheet metal plate machine, will do the work that heretofore required two skilled operatives, or catchers, as they were generally termed. Accordingly, it effects a considerable saving in the cost 80 85 of manufacturing sheet metal plates, for it enables a rolling mill or a machine in which metal plates are rolled to be operated by one operative, namely, a roller instead of by a roller and two catchers, as is now the universal practice. In addition to materially reducing the number of operatives required in a plant, my improved mechanism handles the plates more rapidly and more efficiently than they can be handled by workmen. This 90 95 is particularly true when the mechanism is used in conjunction with a hot mill, for in a hot mill the catchers have to use tongs to lift the plates upwardly into position to be grasped by the roller stationed at the front 100 105 of the mill.

In some classes of work, for example, rolling hot plates, it is desirable to construct the mechanism in such a manner that the cycle of the plate lifters will be merely from their depressed position to their elevated position, or from their elevated position to their depressed position, said plate lifters coming to rest at the end of the cycle and remaining at rest either in their elevated position or in their depressed position until the operator in charge of the machine actuates the clutch or controlling device that causes the mechanism to start operating. In Fig. 8 of the drawings I have illustrated one of the plate lifter carriers 100 of a mechanism constructed in this manner, both carriers of the mechanism being supported and actuated by a means similar to that described in connection with the form of my invention illustrated in Figs. 1 to 7. The rear end of the carrier is connected to its supporting link 101 by a sliding bearing 102 arranged in an elongated opening in the carrier, and the plate lifter 103 on said carrier is rigidly connected to same, it being possible to make the plate lifters of the mechanism rigid instead of hinged, due to the fact that the operator will not feed a plate through the rolls of the mill unless the plate lifters 103 are in position to receive 110 115 120 125 130

the plate. Each plate lifter is preferably provided with a guide 104 so as to prevent a plate from moving off of the supporting table arranged at the rear of the rolls of the mill in the event the plate is discharged from the rolls crooked, as sometimes occurs. In such a mechanism no means similar to the members I and I' and the parts associated with same are necessary, because the plate lifters 10 are rigidly connected to the plate lifter carriers, the clutch controlling cam 38 and co-operating lever 40 are eliminated and the driving mechanism that is arranged between the intermittent shaft H and the cam shaft 8 15 is so designed that the gear ratio between said shafts will be two to one. The mechanism can be started by pulling the locking plunger 43 forwardly so as to permit the clutch member 34 to move into engagement 20 with the co-operating clutch member on the loose gear 33, the end of the plunger 43 thereafter riding on the hub of the cam 134 on the clutch member 34. When the shaft H makes one complete revolution and the cam 25 shaft 8 makes one-half of a revolution, the locking plunger 43 will render the clutch member 34 inoperative, and thus cause the shaft H to come to rest. It will thus be seen that it is necessary for the operator to trip 30 the locking plunger 43 each time he desires to have the plate lifters move either upwardly or downwardly. Another slight change that I prefer to make in the construction of the mechanism, when it is designed 35 for use with a hot mill, is to construct the supporting table at the rear of the rolls of the mill in such a manner that the front end of same can be tilted upwardly by a mechanism under control of the operator at the front of 40 the mill, so as to discharge a hot plate from the table after the rolling operation has been completed. In Fig. 9 of the drawings I have 45 illustrated a table 105 of the character just referred to, said table being pivotally mounted on a supporting structure in such a manner that the front end of the table can be tilted upwardly, as indicated in broken lines in Fig. 9, by depressing an operating device 106 at the front of the mill, which is connected by 50 means of a link 107 to a rock arm 108 secured to the table.

A mechanism of the character just described will not be affected by the heat from the hot plates or the scale that drops off of 55 the plates; it can be made very strong and rigid and it can be built cheaply, due to the elimination of a great many of the parts that are essential when the mechanism is constructed in the manner illustrated in Figs. 1 60 to 7, inclusive.

Having thus described my invention, what I claim as new and desire to secure by Letters Patent, is:

1. A plate lifting mechanism for plate 65 rolling machines, comprising plate lifters

arranged at the rear of the rolls of the machine, carriers to which said plate lifters are connected, and means comprising a counterweighted mechanism and a source of power that drives said mechanism, for bodily raising and lowering said carriers so as to cause the plate lifters to engage a plate that has been discharged from the rolls of the machine and bodily lift or raise said plate into such a position that the operator 75 can grasp the plate and pull it forwardly over the top roll of the machine.

2. A plate lifting mechanism for plate rolling machines, comprising plate lifters arranged at the rear of the rolls of the machine, carriers to which said plate lifters are connected, means comprising a counterweighted mechanism and a source of power that drives said mechanism, for bodily raising and lowering said carriers so as to cause 80 the plate lifters to engage a plate that has been discharged from the rolls of the machine and bodily lift or raise said plate into such a position that the operator can grasp the plate and pull it forwardly over the top 85 roll of the machine, and means for moving the plate lifters relatively to the carriers when said carriers are being lowered.

3. A plate rolling machine, comprising 90 rolls between which the plates are passed, a table or supporting device arranged at the rear of said rolls to receive the plates that are discharged from said rolls, plate lifters at opposite sides of said table which normally occupy an elevated position in proximity to the top roll, and means for causing 95 said plate lifters to move downwardly, remove a plate from said table and thereafter move said plate upwardly into such a position that it can be engaged by the operator 100 standing in front of the machine.

4. A plate lifting mechanism, comprising 105 a vertically-reciprocating member, swinging or oscillating devices pivotally connected to said member adjacent the opposite ends of same for bodily moving said member, and a counterweighted means for rocking or swinging said devices so as to raise and lower said member.

5. A plate lifting mechanism, comprising 115 a member that is adapted to engage a plate and move it upwardly, a counterweighted means for reciprocating or bodily raising and lowering said member, and means for causing said member to assume such a position while it is traveling upwardly that the plate thereon is tilted slightly.

6. A plate lifting mechanism, comprising 120 a vertically-movable member that is adapted to raise a plate, rock shafts provided with 125 devices that are pivotally connected to said member adjacent the opposite ends of same, means for turning said shafts so as to raise and lower said member, and means for varying the pivotal connection between one of 130

said devices and said member so as to tilt or raise one end of said member.

7. A plate lifting mechanism, comprising a vertically movable member, rock shafts 5 journaled in a supporting structure and provided with devices that are pivotally connected to said member, counterweights secured to said rock shafts, a drive shaft, and mechanism arranged between said drive 10 shaft and rock shafts for turning said rock shafts positively in opposite directions so as to raise and lower said member.

8. A plate lifting mechanism, comprising a vertically movable member, rock shafts 15 journaled in a supporting structure and provided with devices that are pivotally connected to said member, counterweights secured to said rock shafts, means for turning said shafts in opposite directions so as to 20 raise and lower said member, and a floating eccentric that forms part of the pivotal connection between one of said devices and said member and which causes one end of said member to tilt downwardly when said member is moving vertically.

9. A plate lifting mechanism, comprising a plate lifter, a carrier to which said plate lifter is connected, rock shafts provided with devices that are pivotally connected to 30 said carrier, an oscillating actuating member, and a rack and pinion mechanism arranged between said actuating member and said rock shafts for raising and lowering said carrier.

35 10. A plate lifting mechanism, comprising a plate lifter, a carrier to which said plate lifter is connected, rock shafts provided with devices that are pivotally connected to said carrier, an oscillating actuating member, a rack and pinion mechanism arranged between said actuating member and said rock shafts for raising and lowering said carrier, and counterweights secured to said rock shafts.

45 11. A plate lifting mechanism, comprising a plate lifter, a vertically movable carrier that supports said plate lifter, rock shafts joined to said carrier and provided with counterweights, an oscillating actuating member for rocking said shafts positively in opposite directions so as to raise and lower said carrier, and means for causing said plate lifter to move relatively to said carrier when said carrier is being raised and lowered.

50 12. A plate lifting mechanism, comprising a plate lifter, a vertically movable carrier that supports said plate lifter, rock shafts provided with devices that are joined to said carrier, an oscillating actuating member for rocking said shafts in opposite directions so as to raise and lower said carrier, and a second oscillating member operatively connected with said plate lifter 60 in such a manner that it causes said plate

lifter to swing into an angular position with relation to said carrier when said carrier moves.

65 13. A plate lifting mechanism for rolling machines, comprising a table arranged at the rear of the rolls of the machine for receiving the plates that are discharged from said rolls, vertically-movable members arranged at the opposite sides of said table in parallel relation to each other and provided with means for engaging a plate positioned on said table and moving said plate upwardly, rock shafts provided with devices that are pivotally connected to said members, a pair of oscillating actuating 70 members arranged at the opposite sides of said table for rocking said shafts so as to raise and lower said members, and a cam shaft provided with cams that are adapted to move said actuating members in opposite directions.

75 14. A plate lifting mechanism for rolling machines, comprising plate lifters arranged at the rear of the rolls of the machine on opposite sides of a table or support that receives the plates as they are discharged from the rolls, vertically-movable carriers to which said plate lifters are connected, a pair of rockshafts associated with each carrier and provided with devices that are 80 pivotally connected to said carrier, counterweights secured to said rock shafts, an oscillating actuating member for each carrier provided with racks that mesh with pinions on said rock shafts, and a cam shaft provided with cams, one of which coöperates with one of said actuating members to rock both actuating members in one direction and the other of which coöperates with the other actuating member to rock both of said 85 actuating members in the opposite direction.

90 15. A plate lifting mechanism for rolling machines, comprising plate lifters arranged at the rear of the rolls of the machine on opposite sides of a table or support that receives the plates as they are discharged from the rolls, vertically-movable carriers to which said plate lifters are connected, a pair of rock shafts associated with each carrier and provided with devices that are 95 pivotally connected to said carrier, counterweights secured to said rock shafts, an oscillating actuating member for each carrier provided with racks that mesh with pinions on said rock shafts, a cam shaft provided with cams, one of which coöperates with one of said actuating members to rock both of said 100 actuating members in the opposite direction.

16. A plate lifting mechanism for rolling machines, comprising plate lifters arranged at the rear of the rolls of the machine on opposite sides of a table or support that receives the plates as they are discharged from the rolls, vertically-movable carriers to which said plate lifters are connected, a pair of rock shafts associated with each carrier and provided with devices that are pivotally connected to said carrier, counterweights secured to said rock shafts, an oscillating actuating member for each carrier provided with racks that mesh with pinions on said rock shafts, a cam shaft provided with cams, one of which co-operates with one of said actuating members to rock both actuating members in one direction and the other of which co-operates with the other actuating member to rock both of said actuating members in the opposite direction, and means for swinging said plate lifters relatively to their carriers comprising cams on said cam shaft, oscillating members co-operating with said cams, and racks on said oscillating members connected by trains of gearing directly to said plate lifters.

17. A plate rolling machine, comprising a table arranged at the rear of the rolls of the machine for receiving the plates that are discharged from said rolls, a plate lifting mechanism arranged at the rear of the rolls and comprising plate lifters that normally lie in a substantially horizontal position in proximity to the top roll of the machine, and an operating mechanism for said plate lifters that causes said plate lifters to swing into a substantially vertical position, move downwardly to a point below the plate lying on said table and thereafter swing back to a horizontal position and move upwardly so as to engage the plate lying on the table and move said plate upwardly into a position to be grasped by the operator standing at the front of the machine.

18. A plate rolling machine, comprising a table or support arranged at the rear of the rolls of the machine for receiving the plates that are discharged from the rolls, a plate lifting mechanism comprising vertically-movable carriers that normally stand in an elevated position in proximity to the top roll of the machine, pivotally mounted plate lifters on said carriers that normally lie in a substantially horizontal position, means for moving said carriers downwardly into proximity to said table and thereafter upwardly to their former position, and means for causing the plate lifters to move relatively to said carriers so as to pass the side edges of the plate lying on the table when said carriers move downwardly and thereafter swing back into a position to engage the plate when the carriers move upwardly.

19. A plate rolling machine, comprising

rolls between which the plates are fed, a plate lifting mechanism arranged at the rear of the rolls of the machine comprising vertically-movable carriers equipped with means for engaging a plate that has been discharged from the rolls of the machine and moving said plate upwardly into proximity to the top roll of the machine, an operating mechanism for said carriers, a clutch for connecting said operating mechanism with some suitable source of power, and means for rendering said clutch inoperative automatically after said carriers have moved downwardly and returned to their normal elevated position.

20. A plate rolling machine, comprising rolls between which the plates are fed, means arranged at the rear of the rolls of the machine for elevating the plates that are discharged from the rolls, an operating mechanism for said plate elevating means, a clutch for connecting said operating mechanism with some suitable source of power, and means for automatically rendering said clutch inoperative comprising a plunger, a rock shaft provided with a member that moves said plunger into position to disengage said clutch, and a cam for controlling the position of said rock shaft.

21. A plate rolling machine, comprising rolls between which the plates are passed, means for driving said rolls, an intermittently operating shaft, a clutch for connecting said intermittent shaft with said driving means, an automatic device for rendering said clutch inoperative, and mechanism arranged at the rear of the rolls of the machine and operatively connected with said intermittent shaft for elevating the plates that are discharged from the rolls and holding said plates in position to be grasped by the operator in front of the machine.

22. In a plate rolling machine, a table or support arranged at the rear of the rolls of the machine for receiving the plates that are discharged from the rolls, vertically-movable plate lifting devices arranged at opposite sides of said table, and means for enabling said plate lifting devices to be adjusted laterally with relation to said table so as to adapt them to plates of different widths.

23. In a plate rolling machine, rolls between which the plates are passed, a table or support arranged at the rear of the rolls for receiving the plates that are discharged from the rolls, vertically-movable carriers arranged at the rear side of the machine in parallel relation to said table and provided with plate lifters, supporting structure carrying mechanisms that operate said carriers, and means for enabling one of said supporting structures to be adjusted laterally with relation to said table.

24. A plate lifting mechanism, comprising

a plate lifter, a pair of rock shafts provided with counterweights, connections between said rock shafts and said plate lifter, and means for rocking said shafts to raise and lower said plate lifter.

25. A plate lifting mechanism, comprising a plate lifter, a pair of rock shafts provided with counterweights, connections between said rock shafts and said plate lifter, means for rocking said shafts to raise and lower said plate lifter, and means for causing one end of said plate lifter to tilt downwardly when said plate lifter is being raised.

26. A plate lifting mechanism, comprising a table that is adapted to receive a plate, vertically reciprocating carriers arranged longitudinally of said table at opposite sides of same, a counterweighted mechanism for bodily moving said carriers upwardly and downwardly, and plate lifters on said carriers that remove the plate from said table when said carriers move upwardly.

27. A plate lifting mechanism, comprising a table that is adapted to receive a plate, vertically reciprocating carriers arranged longitudinally of said table at opposite sides of same, a counterweighted mechanism for bodily moving said carriers upwardly and downwardly, plate lifters on said carriers that assume a substantially horizontal position and remove the plates from said table when said carriers move upwardly, and means for causing said plate lifters to move into an angular position with relation to said carriers when said carriers move downwardly so that said lifters will clear the side edges of the plate lying on the table.

28. A plate lifting mechanism, comprising a table that is adapted to receive a plate, vertically reciprocating carriers arranged longitudinally of said table at opposite sides of same, a counterweighted mechanism for bodily moving said carriers upwardly and downwardly, plate lifters on said carriers that remove the plate from said table when said carriers move upwardly, and a connection between said carriers which causes them to move in unison.

29. A plate lifting mechanism, comprising a pair of vertically-movable carriers arranged in parallel relation on opposite sides of a table that is adapted to receive a plate, means for raising and lowering said carriers, pivotally mounted plate lifters on said carriers whose axes extend longitudinally of the carriers, and means for causing said plate lifters to rock downwardly into a substantially vertical position when the carriers move downwardly and thereafter upwardly into a substantially horizontal position so as to engage the plate lying on the table when the carriers move upwardly.

30. A plate lifting mechanism, comprising a pair of carriers arranged in parallel relation to each other on opposite sides of a table

that is adapted to receive a plate, plate lifters on said carriers, counterweighted rock shafts joined to said carriers in such a manner that they will positively raise and lower said carriers when said shafts are rocked, mechanism for rocking said shafts, a drive shaft, and a clutch under control of the operator in charge of the machine for connecting said drive shaft with the mechanism that operates said rock shafts.

31. A plate lifting mechanism, comprising a pair of carriers arranged in parallel relation to each other on opposite sides of a table that is adapted to receive a plate, plate lifters on said carriers, counterweighted rock shafts joined to said carriers in such a manner that they will positively raise and lower said carriers when said shafts are rocked, mechanism for rocking said shafts, a drive shaft, a clutch under control of the operator in charge of the machine for connecting said drive shaft with the mechanism that operates said rock shafts, and means for automatically rendering said clutch inoperative at the completion of the cycle of operations of said carriers.

32. A plate lifting mechanism for plate rolling machines, comprising vertically reciprocating carriers that normally occupy an elevated position in proximity to the top roll of the machine, a table for receiving the plates that are discharged from the rolls, means under control of the operator in charge of the machine for causing said carriers to move downwardly into proximity to said table and thereafter upwardly into proximity to said top roll, and plate lifters on said carriers that swing into a horizontal position and remove a plate lying on said table when said carriers move upwardly.

33. A plate lifting mechanism for plate rolling machines, comprising vertically-reciprocating carriers that normally occupy an elevated position in proximity to the top roll of the machine, a table for receiving the plates that are discharged from the rolls, means under control of the operator in charge of the machine for causing said carriers to move downwardly into proximity to said table and thereafter upwardly into proximity to said top roll, plate lifters on said carriers that swing into a horizontal position and remove a plate lying on said table when said carriers move upwardly, and means for positively moving said plate lifters relatively to said carriers in such a manner that said plate lifters will clear the plate lying on the table when the carriers move downwardly and will thereafter move into a position to engage the plate when the carriers move upwardly.

34. A plate lifting mechanism for plate rolling machines, comprising a pair of vertically-movable carriers arranged in parallel relation to each other at opposite sides of a

table arranged at the rear of the rolls of the machine, plate lifters on said carriers, a counterweighted operating mechanism for said carriers that normally holds said carriers in an elevated position in proximity to the top roll of the machine, means under control of the operator in charge of the machine for causing said counterweighted mechanism to move the carriers downwardly and then upwardly so as to cause the plate lifters 10 on the carriers to engage and remove the plate lying on the table, and means for causing the plate to assume such a position when the carriers come to rest that the front end of the plate will tilt downwardly toward the 15 top roll of the machine.

THOMAS McCABE.
